INVENTOR.

Charles L. Ford
By J. H. Weatherford
ATTORNEY.

UNITED STATES PATENT OFFICE.

CHARLES L. FORD, OF MEMPHIS, TENNESSEE.

EXTENSION FOR ELECTRIC STARTER BUTTONS.

Application filed March 12, 1925. Serial No. 15,125.

To all whom it may concern:

Be it known that I, CHARLES L. FORD, a citizen of the United States, residing at Memphis, in the county of Shelby and the 5 State of Tennessee, have invented certain new and useful Improvements in Extensions for Electric Starter Buttons, of which the following is a full, clear, and exact description, such as will enable anyone skilled 10 in the art to make and use the same.

This invention relates to improvements in extensions for electric starter buttons and has especial relation to an extension to be used in connection with the starting button 15 or pedal of the so called self-starter for an automobile.

The object of my invention is to make an extension which will provide a larger and firmer member on which to place the heel of 20 the foot in operating such a device as the electric starter of an automobile and to make such a member which may be easily placed on and will secure itself to the starter button and which when so placed will seat 25 firmly and without tendency to be displaced.

I accomplish these objects as will be more fully, hereinafter set out in the drawings, specification and claims.

In the drawings:

30 Fig. 1 is a section of the device taken on the line I—I of Fig. 2 showing in dotted lines the button in connection with which it is adapted to be used.

Fig. 2 is a plan of the member.

35 Referring now to the drawings in which the various parts are indicated by numerals, 1 is the ordinary starter button which is depressed by placing the heel of the shoe thereon in order to operate a type of self starter 40 used on a well known automobile. 2 indicates the floor board through which this button projects and 3 the front seat support showing the proximity of the button to the front of the support. These buttons have a 45 projecting rivet head 4 which prevents the heel firmly seating thereon and are also so

close to the front of the seat support that the heel of a woman's shoe, especially that type known as a French heel, is hard to place thereon and often slips off scarring the 50 heel and often ruining the shoe.

My extension member comprises a disk 5 forming an enlarged button surface preferably roughened as shown to prevent the heel from slipping thereon, from the underside 55 of which disk a hub 6 projects, this hub is bored out making it an annular sleeve or hub to receive the button 1. After being so bored out slots 7 are cut in this sleeve to separate the lower portion into tongues 8 60 which have a certain amount of resiliency and closely embrace and grip the sides of the button. 9 is a central recess adapted to receive the rivet head 4.

The extension member so formed is 65 slipped over the button 1 and forced downward thereon. The resilient tongues 8 securely grip and thereby attach the member to the button. The central recess 9 permits the extension to rest flat upon the top of the 70 button 1 and thereby avoids all tendency towards rocking or displacement.

In use, the extension member is simply pushed down on the starter button, or if necessary tapped lightly with a hammer until 75 it seats solidly in place. The resiliency of the tongues securing it firmly in place.

Having now fully described my invention, what I claim and desire to secure by Letters Patent in the United States is:—

1. In an extension for a starter button, an enlarged disk, having an annular hub projecting downward therefrom and separated into a plurality of tongues.

2. In an extension for a starter button, an 85 enlarged disk having its upper surface scarred or roughened, and having an annular hub projecting downward therefrom and separated into a plurality of tongues.

In testimony whereof I have hereunto set 90 my name.

CHARLES L. FORD.
